UNITED STATES PATENT OFFICE

ANTHONY BARONE, OF BOSTON, MASSACHUSETTS

DENTAL ELEVATOR

Application filed July 12, 1929. Serial No. 377,792.

This invention relates to an improvement in dental elevators. In extracting teeth, or where for any other reason special difficulty is anticipated it is common to employ a hand 5 tool having a blade somewhat like that of a screw driver termed an elevator to loosen the root preparatory to extraction. Heretofore so far as I am aware the elevator so employed has been operated entirely by hand manipulation to loosen or pry out the root 10 or roots on teeth.

The object of the present invention is to provide mechanism for actuating or vibrating the tooth so that the hands of the operator may be left free to simply hold the elevator blade in proper position and shift it from one point to another according to the particular point desired by the operator.

Before explaining in detail the present invention, it is to be understood that the invention is not limited in its application to the details of construction and arrangement of parts illustrated in the accompanying drawings, since the invention is capable of other 25 embodiments and of being practised or carried out in various ways. Also it is to be understood that the phraseology or terminology employed herein is for the purpose of description and not of limitation, and it is 30 not intended to limit the invention beyond the terms of the several claims hereto appended as considered in view of the prior art and the requirements thereof.

In the drawings:

Fig. 1 is a side elevation of a tool embodying the invention attached to the hand piece of a dental engine.

Fig. 2 is a similar view but partly in section.

Fig. 3 is a plan view of the apparatus as shown in Fig. 1.

Fig. 4 is a section on line 4—4 of Fig. 1.

Fig. 5 is a diagram partly in section showing the elevator inserted between the root of a tooth and the root socket in the jaws preparatory to operation.

Fig. 6 is a diagram partly in section showing the root partially separated from the socket.

Referring to the drawings there is shown

at A a dental elevator having a blade 10 provided with a shank or stem 11 and a cylindrical spindle 12 axial with the blade 10. The spindle 12 is provided with a crank arm 13 which may be integral with the spindle 12 55 or made as a separate member attached to the spindle according to convenience in construction and assembling.

The spindle 12 is preferably formed with an extension 14 which serves as a pivot. 60

At B is shown a holder for the elevator having at one end a socket portion 15 for the elevator and having at its other end a socket or tubular portion 16 offset from and parallel with the socket portion 15 adapted for connection with a dental engine or other power mechanism and having an intermediate portion 17 which connects the two socket portions 15 and 16. 65

The socket portion 15 is formed with a cylindrical socket to form a bearing for the spindle 12 and the lower part of the said socket is stepped down to form a bearing for the pivot portion 14 of the spindle 12. 70

At 18 is shown a mandrel having a lower shank portion adapted to be engaged with the jaw of a dental engine or other driving mechanism and having an offset upper portion 19 which engages with an elongated slot 20 in the crank arm 13 of the elevator. 75 If the mandrel 18 is rotated on its axis its angular or offset portion 19 will, by engaging with the slot in the end of the arm 13, cause the said arm to vibrate in the arc of a circle whose center is the axis of the spindle 12 and 80 thereby vibrate the elevator A on its axis. 85

Preferably there are provided ball bearings 21 for the shaft 11 of the elevator.

A holder B is provided with a guide and bearing portions 22 for the mandrel 18. This bearing may be a block or disc held fast in the tubular socket portion 16 either by a tight fit or by other suitable means. 90

The body of the holder B may be a single casting or a plurality of portions fastened together. As shown in the drawings, it consists of a single casting and is formed with holes adapted to be closed by screw plugs 23, 24. This, however, is a matter of con- 95

venience and choice in construction as it is not essential that the holder be integral.

Any suitable mechanism may be provided for rotating the mandrel 18 on its axis. Preferably it is so constructed that it is adapted to be operatively connected with one of the usual dental engines and is shown in Figs. 1 and 2 as so connected.

At C is shown such an engine of well-known construction. At 25 is shown the rotary tubular spindle of the engine having spring jaws 26 between which the non-circular shank 18 of the mandrel is inserted. The spring jaws 26 will grip the non-circular shank 18 of the mandrel so that when the spindle 25 of the engine is rotated it will cause the mandrel 18 to rotate and the outer end of the offset portion 19 will move in a circular path. By reason of the engagement 20 of the crank arm 13 with the elongated slot 20, said crank arm will vibrate in the arc of a circle and cause the elevator blade 10 to vibrate on its axis. On account of the flattened form of the blade 10 the edges of the 25 blade will vibrate in the arc of a circle and will exert a sort of prying action on the root 29 of the tooth thereby prying it from the fibers which bind the root to the jaw 30 and gradually work into the socket until the root is loosened as shown in Fig. 6. The tooth will then either fall out or can be easily pulled out with the fingers.

The form of the device shown in the drawings is especially used for extracting roots 35 from the upper jaw but in some cases can well be used in extracting teeth from the lower jaw. For use on some teeth in the lower jaw the angle of the blade A to the intermediate portion 17 of the holder B may 40 be greater or less than 90°.

It should be made at such a point as will be most convenient for use according to the teeth on which it is to be used.

In using the device the elevator blade is 45 inserted between the root and the wall of the socket and the engine is then turned on. The operative end of the blade will be vibrated and the root will be loosened in the socket or separated from the wall of the 50 socket by breaking the holding fibers so that the tooth can be easily extracted.

What I claim:

1. In combination with a dental elevator blade for use in loosening roots of teeth from 55 the root socket, said blade being provided with a spindle, a holder having a socket which forms a bearing for the said spindle, an arm connected with said spindle and means operatively connected with the said 60 arm for vibrating the arm and thereby swinging the elevator blade on its axis.

2. In combination with a dental elevator having a spindle, a holder having a socket portion which forms a bearing to receive the 65 spindle, a rotary driving member, means

for making a driving connection between said elevator spindle and said driving member and means whereby when said driving member is rotated the dental elevator will be caused to vibrate on its axis.

3. Mechanism for use with a dental elevator blade to loosen the roots of teeth in the root socket, said blade having a spindle shank, a holder having a socket portion which forms a bearing to receive the elevator spindle, a rotary driving member, means for making a driving connection between said elevator spindle and said driving member and means whereby when said driving member is rotated the dental elevator will be caused to vibrate on its axis.

4. In combination with a dental elevator having a blade and a spindle shank, a holder having a socket within which the elevator spindle is journalled, an arm connected with 85 said elevator spindle, means for operatively connecting said arm with a rotary driving member and means whereby the rotation of said driving member vibrates said arm and thereby vibrates said elevator on its axis.

5. In combination with a dental elevator having a blade and a spindle shank, a holder having a socket within which the elevator spindle is journalled, an arm connected with said elevator spindle, means for operatively connecting said arm with a rotary shaft of a dental engine and means whereby the rotation of said shaft will vibrate said elevator.

6. In combination with a dental elevator having a blade, a holder having a bearing in 100 which the elevator is journalled, an arm projecting from the said elevator and having an elongated slot, a mandrel journalled in said holder and having an offset portion, said offset portion engaging with the slot in said arm, means for making a driving connection between said mandrel and a dental engine whereby said mandrel is rotated and means whereby when said mandrel is rotated said elevator will be vibrated on its axis.

7. In combination with a dental elevator having a blade, a holder having a bearing in which the elevator is journalled, an arm projecting from the said elevator and having an elongated slot, a mandrel journalled in 110 said holder and having an offset portion, said offset portion engaging with the slot in said arm, and means for rotating said mandrel whereby said elevator arm is vibrated thereby 115 vibrating the elevator.

8. In combination with a dental elevator blade for use in loosening roots of teeth from the root socket, said blade being provided with a spindle, a holder which forms a bearing for the said spindle, and means operatively connected with the said spindle for vibrating the elevator blade on its axis.

9. In combination with a dental elevator having a spindle, a holder having a bearing 130

to receive the spindle, a driving member, means for making a driving connection between said elevator spindle and said driving member and means whereby when said driving member is operated the dental elevator will be caused to vibrate on its axis.

In testimony whereof I affix my signature.
ANTHONY BARONE.
